FRANCIS I. DU PONT, OF WILMINGTON, DELAWARE, ASSIGNOR TO DELAWARE CHEMICAL ENGINEERING COMPANY, OF WILMINGTON, DELAWARE, A CORPORATION OF DELAWARE.

PROCESS OF AND APPARATUS FOR OBTAINING OXIDS OF NITROGEN FROM ATMOSPHERIC AIR.

1,311,594.

Specification of Letters Patent. Patented July 29, 1919.

Application filed March 26, 1915. Serial No. 17,116.

To all whom it may concern:

Be it known that I, FRANCIS I. DU PONT, a citizen of the United States, residing at Wilmington, county of New Castle and State of Delaware, have invented a new and useful Improvement in Processes of and Apparatus for Obtaining Oxids of Nitrogen from Atmospheric Air, of which the following is a full, clear, and exact description, reference being had to the accompanying drawings, which form a part of this specification.

It is well understood that when a mixture of oxygen and nitrogen is raised to a certain high temperature, a combination takes place and oxids of nitrogen are formed. Usually, the heating is accomplished by means of an electric arc because, by this means, an intense heat is obtainable without depending upon the walls of the chamber in which the heating is accomplished. In other words, the electric arc produces an intense heat and will, itself, keep the heat away from the walls of the chamber provided the electrodes are sufficiently far away. As the temperature required is greater than any material, except carbon, will stand, and as carbon cannot be used on account of its affinity for oxygen, it is generally recognized that no method of heating, other than the electric arc, is practicable.

In the utilization of the electric arc many inventors have proceeded on the theory that by forcing a maximum amount of atmospheric air through the arc, or by diffusing the arc throughout a great volume of space, the best results will be secured. An appreciation of the nature of an electric arc and of the conditions most favorable to its formation will make it evident that the results sought are impossible of accomplishment and that the formation reaction that occurs proceeds in spite of, and not because of, the special but mistaken means employed to promote it.

An arc appears to the eye as a streak of light between two electrodes. Up to a certain point, gases are a better conductor of electricity in proportion as they reach a state of great rarity. Maximum conductivity, therefore, is at a point where there is very little gas in the space through which the current is traveling. From this it is

apparent that the electric arc consists in air heated to such an extent that it is greatly rarefied. Therefore the condition automatically exists that actually within any given arc there is very little air.

It will, therefore, be appreciated that it is impossible to pass enough air through an arc to produce oxids of nitrogen in commercial quantities. It will also be appreciated that the attempt, by diffusion of the arc, to force the same through a relatively large volume of air, is likewise necessarily ineffective. The greatest amounts of oxids produced in such processes are doubtless produced in close proximity to, but not actually in, the arc.

The object of my invention is to bring the greatest possible volume of air in close proximity to, but out of the path of, an arc of high current density. The execution of this process involves the employment of a relatively long and narrow chamber or tube. Further objects of the invention are: to avoid disturbing the natural axial position of the arc in the tube, to render the tube wall non-conductive even with an arc of high current density, to prevent burning out of either electrode, to avoid the danger of displacing, disrupting or short circuiting the arc, and, in general, to provide an apparatus operating on a principle which takes the utmost advantage of the physical characteristics of an electric arc hereinbefore discussed.

A preferred construction of apparatus embodying my invention and adapted to carry out the process embodying my invention is shown in the drawings, in which—

Figure 1 is a longitudinal view, principally in section, of the entire apparatus. Fig. 2 is a cross section through the center of the apparatus. Fig. 3 is a detail sectional view of the air discharge end of one of the electrodes. Fig. 4 is a diagrammatic perspective view showing direction of the air currents in the reaction tube.

A cylinder *a* composed of two parts connected at the center as hereinafter described, has ends *c* through which and the cylinder extends a tube *b*, which is also composed of two parts connected at the center as hereinafter described. The tube *b* projects beyond the cylinder at each end. Surrounding each

end of tube *b* is packing confined, by a ring *d*, against a boss *e* on which the ring is threaded.

5 Into each end of tube *b* extends an electrode *f*. Each electrode is slideable in a head *g*, which abuts against the end of tube *b*. Packing surrounds each tube *b* and is held between the head *g* and a ring *h* surrounding the tube and threaded on the head.

10 A stuffing box *i* is applied to each electrode and the corresponding head.

By the described construction the cylinder *a* is rendered water tight and the tube *b* gas tight.

15 The outer end of each electrode is carried by a holder *k*. The two holders are connected to opposite poles of a source of electric current supply. Each holder *k* (which is of electrically conductive material) is

20 supported on legs *l* (of non-conductive material) extending upward from a slide *m* slideable longitudinally, or in the direction of extension of the cylinder *a*, tube *b* and electrodes *f*, in ways on a base *n*.

25 The two slides are operable in unison in opposite directions. To so operate them I have shown each slide provided with a longitudinally extending rack *o*. Between and engaging both racks is a pinion *p*.

30 It is obvious that by turning pinion *p* the two electrodes may be moved toward each other and into contact to close the circuit and then caused to recede from each other to establish the arc.

35 Each electrode is a hollow rod having an enlarged end in front of which is carried a block of carbon *q*, constituting a pole or the electrode proper. Each holder *k* is connected by means of a rubber hose *r* with a com-

40 pressed air supply pipe *s*; the holder being hollow to permit of the passage of air therethrough to the electrode.

The end wall of each electrode is provided with perforations *f'* which extend at an 45 oblique angle to a plane at a right angle to the axis of the tube, thereby causing the air to enter the tube with a spiral motion, producing a vortex through the central cavity of which the arc is adapted to pass.

50 It has hereinbefore been stated that the tube *b* is made in two halves. The inner ends of the tubes are flared outward to form a central chamber *b'*. The inner flared ends of the tubes have opposing annular flanges

55 between which is confined the neck of a ring *t*. Rings *u*, within the cylinder *a*, confine the flanges of the tube *b* against the neck of the ring *t*. Packing rings are confined between said flanges and the ring neck

60 and between said flanges and the rings *u*. The body of the ring *t* has an annular passage *t'* which communicates, by passages *t'* extending through the neck of the ring, with the central chamber *b'*. The passages *t'* ex-

65 tend in a plane at right angles to the axis

of the tube but at oblique angles to intersecting radii, their direction of extension being such as not to affect the vortex motion of the outflow of air from chamber *b'* and not to cause any air currents which might blow the arc to one side.

The ring *t* connects with an outflow pipe *v* which carries off the combined gases to the concentrating plant.

The cylinder *a* communicates at one end 75 with a water inflow pipe *w* and at the other end with a water discharge pipe *x*. A pipe *y* connects the two ends of the cylinder.

The cylinder *a* is of glass and the tube *b* 80 is of silica.

In operation the electrodes are brought together to close the circuit and are then moved outward in opposite directions, establishing an arc. Water is admitted to the cylinder so that the tube *b* is water cooled. 85 The application of a cooling medium to the tube is of importance, as otherwise the tube, although of non-conducting material, would become conductive at the high temperature which my process contemplates, resulting 90 in short-circuiting of the arc.

When air is admitted through pipes *r* it passes from each end of the tube to the center thereof in the paths indicated in the diagram, Fig. 4. It is important that the 95 whirling motion of the air in both ends of the tube should be in the same direction around the axis of the tube, so that when the gases reach the central chamber there will be no conflicting currents.

The arrangement is such that the main body of the air traversing the tube does not pass through the arc but around it and in close proximity thereto.

The purpose and function of the air current in my process is not to use it as a means to maintain the arc stable. On the contrary the problem is to maintain the arc in the axial position which the arc would normally occupy if there were no current of air passing through the tube and at the same time bring the maximum amount of air in close proximity to the arc.

The problem is solved by the described method of admitting the air, with the resultant whirling motion described, within a cooled insulating tube of relatively small diameter. The action may be explained as follows:

Owing to the action of centrifugal force 120 whereby the coolest and heaviest air tends away from the center of the tube and the hottest and therefore lightest air tends to remain in the center of the tube, it is manifest that the normal axial position of the 125 arc, that is to say, the position which the arc would normally occupy if there were no current of air passing through the tube, is not disturbed by the current of air.

Owing to the cooled insulating tube, the 130

5 axial position of the arc and the centrifugal action of the whirling mass of air, a greater amount of air can be brought into close proximity to an arc than is possible any other way. By maintaining the wall of the reaction tube non-conducting, they may be brought in close proximity to the arc without danger of short circuiting.

10 The enlarged central chamber, together with the oblique exit passages arranged around its periphery, are also of importance, in that thereby the suction produced by the outgoing gases operates equally in all directions and therefore does not tend to dis- 15 place the arc.

It is also necessary to guard against the overheating of one or both electrodes. Experience shows that where the gases travel from one electrode to the other, the latter 20 soon burns out. The provision, in my invention, whereby the air travels from both electrodes toward an intermediate outlet, instead of from one electrode to the other, avoids overheating either electrode.

25 In this specification the word "air" has been used. I wish to say that this is intended to include all mixtures of oxygen and nitrogen, including those in which the air is enriched in oxygen.

30 Having now fully described my invention, what I claim and desire to protect by Letters Patent is:

1. The process of forming oxids of nitrogen from mixtures of oxygen and nitrogen which consists in forming an electric arc, 35 passing the gases to be acted upon in two streams flowing along the arc toward each other, causing the gases at the juncture of the two streams to escape outwardly, maintaining the walls of the reaction chamber non-conducting up to the point of escape for the gases, and cooling the gases during their outward flow away from the arc at the junction of the two streams.

40 2. An apparatus of the character described comprising two alining tubular members having gas inlets, an intermediate connecting chamber of substantially greater diameter than the tubular members and 45 provided with means for the escape of gases, and chambers for a cooling medium on opposite sides of the intermediate chamber and surrounding the respective tubular members and adapted to maintain said cooling medium in contact with the tubes as far as the inner opposite extremities of the same and with the side walls of the intermediate chamber.

50 3. An apparatus of the character de- 55 scribed comprising a tube, poles within the tube between which an electric arc is formed, gas inlet ports arranged to create a vortex within the tube, and gas outlet ports arranged obliquely to intersecting radii of the

4. An apparatus of the character described comprising a tube forming a reaction chamber, poles between which an electric arc is formed, gas inlet ports in the end of the reaction chamber extending obliquely to planes at right angles to the axis of the tube, and gas outlet ports arranged parallel to planes at right angles to the axis of the tube and obliquely to intersecting radii of the tube. 75

5. An apparatus of the character described comprising a tube, hollow electrodes projecting into opposite ends of the tube, poles carried by said electrodes, and gas ports in the front end walls of both elec- 80 trodes.

6. An apparatus of the character described comprising a tube, hollow electrodes projecting into opposite ends of the tube, poles carried by said electrodes, gas inlet 85 ports in the front end wall of both electrodes, and gas outlet ports communicating with an intermediate part of the tube.

7. An apparatus of the character described comprising alining tubular portions 90 having gas inlets and an enlarged central portion having means allowing the escape of gases, two cooling chambers inclosing the tubular portions of the reaction chamber, and means allowing the circulation of a cool- 95 ing fluid between the two cylindrical chambers.

8. An apparatus of the character described comprising a tube forming a reaction chamber, a hollow electrode projecting 100 into said tube, a pole carried by said electrode, and gas inlet ports in the front end wall of the electrode, the axis of said ports arranged obliquely to planes at right angles to the axis of the tube. 105

9. An apparatus of the character de- 110 scribed comprising two alining tubular members having gas inlets and provided with enlarged opposing ends, poles in proximity to the gas inlets, a ring confined between the peripheries of said opposing ends, and gas outlet ports in said ring.

10. An apparatus of the character de- 115 scribed comprising two alining tubular members having gas inlets and provided with enlarged opposing ends, poles in proximity to the gas outlets, and a hollow ring having a ported neck confined between the peripheries of said opposing ends.

11. An apparatus of the character de- 120 scribed comprising two alining tubular members having gas inlets and provided with enlarged opposing ends, poles in proximity to the gas inlets, two cylindrical water-chambers surrounding the respective tubular members, a ring separating said chambers and confined between the enlarged opposing ends of the tubular members, and gas-discharge ports in the ring. 125

12. An apparatus of the character de- 130

- scribed comprising a reaction chamber, gas inlets at opposite ends thereof, a ring surrounding the central portion thereof and provided with ports affording gas outlets 5 from the reaction chamber, two cylindrical water chambers separated by said ring and surrounding the two halves of the reaction chamber, a water discharge pipe communicating with one water chamber, a water 10 admission pipe communicating with the other water chamber, and a pipe connecting the two water chambers.
13. An apparatus of the character described comprising a relatively long and 15 narrow reaction chamber having gas exits opening from the central portion thereof, hollow axially movable electrodes entering opposite ends of the reaction chamber, said electrodes having enlarged ends provided 20 with ports for admission of gases to the reaction chamber and pole pieces carried by and projecting in front of said electrode ends.
14. An apparatus of the character described comprising a relatively long and 25 narrow reaction chamber having gas exits opening from the central portion thereof, hollow axially movable electrodes entering opposite ends of the reaction chamber, poles 30 carried by the electrodes, said electrodes being ported to allow gases to pass from their interior to the reaction chamber, and means to move said electrodes toward and from each other.
15. An apparatus of the character described comprising a relatively long and 35 narrow reaction chamber having gas exits opening from the central portion thereof, hollow axially movable electrodes entering opposite ends of the reaction chamber, poles 40 carried by the electrodes, said electrodes being ported to allow gases to pass from their interior to the reaction chamber, hollow holders carrying said electrodes, air 45 inlets communicating with the holders, and

means to move the holders toward and from each other.

16. An apparatus of the character described comprising a relatively long and narrow reaction chamber having gas exits 50 opening from the central portion thereof, hollow electrodes entering opposite ends of the reaction chamber, poles carried by the electrodes, said electrodes being ported to allow gases to pass from their interior to the reaction chamber, hollow holders carrying 55 said electrodes, air inlets communicating with the holders, slides one for each holder, means to support and insulate each holder from its slide, and means to operate said slides in unison.

17. An apparatus of the character described comprising a relatively long and narrow reaction chamber having gas exits opening from the central portion thereof, 60 hollow axially movable electrodes entering opposite ends of the reaction chamber, poles carried by the electrodes, said electrodes being ported to allow gases to pass from their interior to the reaction chamber, means 65 to slide said electrodes toward and from each other, and heads applied to opposite ends of the tube and through which the electrodes respectively slide.

18. An apparatus of the character described comprising two alining tubes, poles 70 in the respective tubes between which an electric arc is formed, gas inlet ports in the respective tubes, and a chamber, between and communicating with the tubes, provided with means allowing the escape of 75 gases and of a diameter substantially greater than that of the tube.

In testimony of which invention I have hereunto set my hand at Wilmington, Del., 80 on this 22nd day of March, 1915.

FRANCIS I. DU PONT.
